HILAND R. FARNSWORTH, OF SANDUSKY, OHIO, ASSIGNOR TO THE PAPER & TEXTILE MACHINERY COMPANY, OF SANDUSKY, OHIO

GEARLESS PIVOTED SUCTION ROLL

Application filed March 15, 1928. Serial No. 261,713.

The present invention relates to paper making machinery and more particularly to a suction roll gearless drive or means for driving or revolving the perforate shell of the 5 roll by other than gears.

It has been common practice in recent years to drive the shell by direct intermeshing gears, one gear being rigidly fixed to the shell at or near one end, in any suitable or well 10 known manner. Necessarily, this increased the over-all diameter by the difference between the exterior diameters of the shell and gear, making a larger and more cumbersome roll at that end. In the gear driven type 15 there is a considerable loss of power through friction of the engaging gear teeth—roughly, 20% or more. In the gear driven type there are, obviously, at least two intermeshing gears between the in-drive shaft and the roll which 20 it drives. Clearly, extra gears in the gear driven roll, as compared with the gearless drive, give added opportunities for repairs and other recognized disadvantages including the stoppage of the machine for the 25 repairs to the gear drive.

The main objects of the present invention are to avoid this and other recognized difficulties met with in the gear driven roll.

In order to more clearly disclose the construction, operation, and use of the invention, reference should be had to the accompanying drawings forming part of the present application. Throughout the several figures of the drawings like reference characters designate 35 the same parts in the several views.

In the drawings:

Fig. 1 is a central vertical longitudinal cross section through one preferred form of the invention.

Fig. 2 is a cross section on line 2—2 of Fig. 1 looking in the direction of the arrows.

Fig. 3 is a right hand end view of Fig. 1, with the drive omitted.

Fig. 4 is a left hand end view.

Fig. 5 is a lateral cross section on line 5—5 of Fig. 1 looking in the direction of the arrow and showing the right hand end of the shell, and

Fig. 6 is an enlarged fragmentary cross see-

tional view through the reduced neck and outer shell bearing.

Referring to the drawings in detail 1 indicates the usual perforated suction roll shell at present widely used in paper making machines. These shells under actual working conditions are driven at a high rate of speed, and therefore, practically necessitate the use of antifriction bearings between them and the relatively stationary supports about which 55 they revolve, as will be later disclosed.

Extending longitudinally throughout the interior of this shell is the usual stationary suction box 2. The body or greater part of this box and especially that part which co- 60 operates with the shell to make the seal is substantially the same as in the rolls in general use for a number of years past. Specially constructed members at opposite ends of the shell have been provided to make it possible to combine with the shell a simple and compact form of gearless drive through which the shell may be directly driven from the in-drive shaft itself, without interposition of any gears. The opposite ends of the suction 65 box are also changed to carry elements which co-operate with the specially constructed members at the opposite ends of the shell so that the antifriction bearings of the shell 70 may be interposed between such co-operating 75 elements, all as will later appear in detail.

In this construction the suction is taken from the front end, the pump being suitably connected there.

To the drive end of the shell a head 5 is 80 bolted or otherwise securely fastened in order to drive the shell through said head. The head 5 is provided with suitable hand holes or openings through which a deckle and deckle rod may be moved as will be later disclosed. Preferably, the head 5 is provided with an inwardly extending shoulder flange 90 6 which overlies and engages the inner wall of the shell adjacent the end. This arrangement, while acting to center the head, in assembling, also acts to substantially brace that end of the roll outwardly from the head. It will be noticed, also, that the head overlaps and engages the end wall of the shell, acting 95 as a further positioning means and a brace to 100

the shell in that direction—longitudinally. It is through this overlapping flange or ring that the fastening screws are passed and turned into the end wall of the shell.

5 The head 5 is provided with an outwardly extending elongated tubular journal 7 of reduced diameter. This journal is mounted on suitable roller or other antifriction bearings 8, the inner race 8a of which has its inner end 10 abutting against the shoulder 7a. These bearings may be mounted in any one of a number of usual and well known ways in a standard frame, or suitable roll support 9, with suitable outer cap plate. As in general 15 practice, they are made in upper and lower halves or sections, separably connected.

To avoid any possibility of a longitudinal movement of the bearings 8 relative to the journal 7 in an outer direction, a collar or like 20 device 19 is provided on the tubular journal 7 in contact with the outer end of race 8a and adapted to be seated in cooperating channels, recesses or the like 20, in said journal 7.

At the opposite end of the shell is disposed 25 another annular plate or head of L-shaped cross section having flanges 10 and 11 at right angles, the radial flange 11 being provided with hand holes for operation of deckles, as in the case of the corresponding flange at the 30 opposite end of the shell. The flange 10 fits snugly within the shell end, as in the case of the corresponding flange of the annular plate at the opposite end, is provided with a narrow radial flange 14 which overlaps and engages 35 the adjacent shell end and through which screws or the like may be threaded to secure the shell and head together. At this end an annular plate 12 is secured to the flange 11 for a purpose to be later disclosed. From the radial flange 11 an annular flange 13 extends at 40 right angles and longitudinally inwardly of the shell. From the inner edge of this longitudinal flange extends a fifth flange 4, parallel with and spaced, considerably, from the 45 plate 12. At the suction end of the roll the suction box is provided with a longitudinal socket 15 of reduced diameter corresponding approximately to the diameter of the central opening through the annular plate 12. Socket 50 et 15 is adapted to snugly receive the inner end of a tubular journal 16, an annular shoulder 16' on the journal, contacting the end of the suction box to limit insertion of the journal in the socket. That part of the tubular journal lying beyond the end of the suction 55 box is mounted in the antifriction bearings of the shell and in the upper end 17 of a standard or like suitable support, the lower half of which, preferably, is made detachable 60 for removal and replacement of the well known Fourdrinier wire. The upper half of the standard is suitably concaved to seat the outer portion of the tubular journal and is provided with lateral flanges to receive 65 clamping bolts. A concave plate or clamp 18

is drawn into tight clamping position about the tubular journal end by bolt and nut or other suitable means. This clamping action is such as to completely prevent all movement of the tubular journal and attached suction box, in any direction relatively to the standard. If it is desired to adjust the box angularly within the shell, at any time, it is only necessary to slightly loosen the clamp plate 18, rotate the box to the desired position, and re-clamp. At the opposite end of the roll, the suction box is provided with a socket 21 in which is securely fixed or seated a stub shaft 22 which extends completely through the reduced journal 7, in spaced relation thereto.

The outer end of this stub shaft is reduced and has the outer portion of such reduced end slightly tapered as at 23 to receive the tubular portion of a removable nut 25 having a cooperating taper and provided with a threaded opening to receive the threaded central reduced extension 26 of the stub shaft. A suitable lock nut 27 may be used to prevent loosening of the nut 25. The inner section of the nut 25 is provided with a radial wall, flange, or shoulder 28 which acts as a stop or inward limit for the inner race of the anti-friction bearing 30. This bearing, as will be clear, is adapted to be seated upon the cylindrical face or wall of the member 25. When in position it is retained by a lock nut or ring 29 threaded upon the outer threaded portion of the nut 25. The co-operating tapers of said nut and stub shaft act as a quick automatic centering means. Said nut 25 is always correctly aligned with the driving shaft and consequently, when in place on said stub shaft will maintain proper alignment of the same. The whole bearing and its support may be removed and replaced, as a unit, by simply removing the lock nut 27 and cap nut 25, as will be evident. The bearing 30 is, of course, concentric and carried by the nut 25 and extends radially from the nut to the inner wall of the reduced journal 7, thereby supporting 100 that end of the shell the bearing 30. As a protection to a radial shoulder 3 is formed in the reduced end of journal 7 a short distance inwardly of bearing 30 to intercept any water that might flow along the inside of the shell toward the bearing. Between this shoulder and the bearing is disposed a water tight packing ring, as a further protection.

For driving the shell, a short removable shaft section 31 is provided having a flange 32 through which clamping bolts 33 pass into the end of the journal 7, or into lugs thereon. A flexible coupling of any usual and well known type connects this removable section direct to the regular in-drive shaft for operating the roll.

At the opposite or suction end, the roll is supported by the tubular journal and co-operating socket end of the suction box, the outer or free ends of the journal being seated 130

on the corresponding standard. The shell, at that end, is also supported on and by the tubular journal, by an interposed antifriction bearing 40. These bearings comprise the inner and outer races with rollers or like anti-friction elements between. The bearing as a whole is housed between plate 12, flanges 4 and 13, and a bearing carrier sleeve 41. Sleeve 41 is constructed to be screwed snugly 10 on the tubular journal and into position to complete the housing of the bearing when all parts are in their proper operative positions. It is provided with an inner radial flange 41 which acts as an engaging wall for the bearing, and by which the bearing, as a unit, may be withdrawn with the carrier sleeve. To make a tight closure from the outside of the end of the roll for the bearing, a ring or gasket 43 is provided. This is threaded onto 20 the outer face of the carrier and between it and the adjacent edge of plate 12, completely filling the gap and making a water tight closure. In the construction shown, the shoulder 16' acts as a limit to the inward movement 25 of the carrier 41, to quickly and correctly position it. This is a preferred, though not an essential arrangement. After the carrier, with its bearing, has been properly placed, it may be secured against loosening by set 30 screws or the like. The plate 12 and gasket 43 are then secured in place. It will be seen that the shell end is then supported on the tubular journal by the interposed antifriction bearings.

35 As a further precaution against entrance of water and foreign matter into the housing of the antifriction bearing 40, guard plates 44 and 45 are provided between the end walls or edges of the bearing races and the flange 4. 40 They are annular, one having a central opening of greater diameter than the other, both concentric with the tubular journal and so arranged that they overlap each other and contact along the overlapping areas. Also, they 45 are so arranged and proportioned that they extend, radially, the full inner width of the bearing housing, one of them being provided with a shoulder 46 to space it laterally from its bearing race so that it will maintain a 50 parallel relation to the other. For like reason, the flange 4 is cut away, radially, to receive or seat such portion of the same guard member as overlies and is in contact with the other member, leaving a shoulder abutting 55 the remaining part of the other guard member to hold it snugly in operative position.

80 Preferably, the suction connection is made by an elbow pipe having a horizontal branch which is removably clamped to the outer or free end of the tubular shoulder 16, as previously set forth. The other or vertical branch, is made as short as practical, so that the distance from the longitudinal axis of the roll to the lower edge of said branch, when 65 disconnected from the suction pipe proper,

will be less than the exterior radius of the shell. Connections between this branch and the suction pipe may be the same as or similar to those between the other branch and the tubular journal. This will permit easy and quick disconnection. Thus, to replace a wire, it is only necessary to disconnect the suction pipe, unbolt the section of the standard at that end, raise the end to remove the "loose piece", slide off the old wire, and replace 75 the new wire.

It will be noticed that the flange 4, adjacent its inner edge, is returned upon itself to provide a small outwardly directed flange with its edge 47 toward the inner surface of the shell. This, of course, rotates with the shell at high speed. Water tending to run along flange 4 and inwardly to the bearings will be caught here and thrown back, centrifugally, from this edge. As a further safe guard, a series of small drainage perforations 48 are provided for escape for any water which might get into the housing. Suitable oil holes are also provided, of course. At the opposite end of the roll possible seepage of water along the stub shaft 22 toward the bearing at that end is prevented by breaking the continuity of the surface of the suction box end and the stub shaft, as shown. In the case of the suction 95 box end, it is grooved circumferentially to provide, longitudinally, alternate channels and angular ridges 47a to collect the moisture so that it will drip off radially. With the stub shaft, a ring or washer of suitable 100 shape, and operating in the same way is used. Many changes in details to accomplish the same result may be made and it is not intended to limit the present case to those disclosed.

105 It should be borne in mind that, though the suction box is a separate construction relatively to its supporting means—the stub shaft and the tubular journal—they are nevertheless, tightly fitted into their respective sockets in the box ends and there is no relative movement between them and the box after the roll has been completely assembled and is ready for operation. Consequently, the position of the suction box, within the shell, is unchangeable. It cannot be drawn against the inner surface of the roll and cause the great damage and loss of power otherwise frequently occurring. Nor can it move way from the shell and cause leakage and consequent failure of operation. The 110 box is kept accurately and rigidly in a definite fixed operative position.

One great trouble in suction rolls for Fourdrinier machines has been the adjustment of the deckles to accord with the varying widths of paper made on the same machine at different times. Whenever an adjustment is to be made, it is necessary to stop the machine because the rods for adjusting are inside 115 120 125 130

and must be reached through hand holes through the rotating shell ends. In the present invention this is completely eliminated and the deckles may be easily and quickly adjusted as much and as often as desired, while the machine is going at its highest speed. Needless to say, the operation is very much safer. In the preferred form, as shown in Fig. 1, the opposite deckle rods 100 are extended inwardly toward the center of the roll instead of outwardly as is usually the case. The inner end of each is detachably connected to the upper end of a radially extending post 101 the lower end of which is considerably enlarged, bored and screw threaded to receive and cooperate with a screw threaded rod 102 and 103, respectively. The rod 102 is a solid rod journaled at its inner end in a web in the bottom of the suction box and provided with suitable stops to prevent longitudinal movement in either direction. It extends longitudinally through rod 103 which is tubular and which, at its inner end, is similarly mounted in a bearing block in a second web in the suction box. Rod 103 is threaded through the base of the other post. Thus, rod 103 provides a support and conduit or passage for rod 102, but they are both operable entirely independently of each other. The two rods are extended outwardly through the tubular journal and elbow connection, suitable air tight glands or stuffing boxes being provided where they pass through the elbow and where the inner one extends beyond the outer one. Each is provided with a suitable nut or head by which it may be independently operated to move its respective deckle as desired. If desired, the threading on the rods may be opposite, to move the deckles oppositely when the rods are rotated in the same direction. Longitudinal movement of rod 103 is prevented by nuts 104 keyed to it on opposite sides of its supporting web, as will be clear on reference to Fig. 1. Should it be desired to remove or repair a deckle, the present invention is particularly practical. It is only necessary, after stopping the machine and aligning the respective hand holes with the particular deckle, to then operate the corresponding rod until the deckle passes outwardly through the hand hole far enough to be conveniently reached. It may then be quickly removed or repaired, the rod operated reversely until it is back in its original position, and the machine again started. While the rods 102 and 103 have been shown as substantially co-axial with the longitudinal axis of the roll that arrangement is, of course, not necessary. It is essential that they should be so placed as to have freedom of movement, independently of the rotation of the roll, so that they may operate freely at all times. One of the simplest and most practical arrangements for accomplishing this result is that shown, with the

rods extending through the lower part of the relatively stationary box and near the longitudinal center of the roll. Power for driving may be transmitted through flexible drive transmission or through a rigid shaft, as desired. In either instance, connection between such transmission and the removable drive shaft section may be made by any one of a number of well known constructions forming no part of the present invention and neither shown nor described in this application, as it is felt that such showing or description would add nothing to the clearness thereof.

At the drive end of the roll the standard for supporting it is of special construction and particularly designed to permit the roll, as a unit, to be swung vertically upward about a center just a slight distance below the outer antifriction bearing of the journal. Such upward swinging of the roll is particularly desirable for the removing and replacing of wires. The pivotal mounting comprises an upper section or bearing block 36 of the roll support 9, a lower section or base 37 secured in any suitable and well known manner to said block by a pivot bar or rod 38 arranged horizontally and at right angles to the longitudinal axis of the shell. Thus by removing clamp plate 18 at the suction end and disconnecting the suction pipe elbow, the suction roll may be swung vertically upward about its pivot to any desired extent. In this connection, it should be borne in mind that the average roll is very heavy. They run from 10" to 40" in diameter and vary proportionately in length. Likewise, of course, the weight varies in proportion to the size. The smallest weighs close to a ton and there are very few of this smaller size in use. They are, clearly, unwieldy and cumbersome. In removing and replacing wires, traveling cranes capable of lifting very heavy loads are used. Necessarily, the lifting power is great and, therefore, capable of causing great damage if not checked at the right point. In the usual construction, and practice, there is no pivot in the support of either end. It then becomes necessary to loosen the sole plate or base plate bolts at the rear or drive end to permit the slight "give" or tilting movement necessary to lift the opposite end of the roll enough to permit the lower removable section 39 to be slid out after unbolting in the usual manner. The lower section extends up slightly beyond the shell wall so that when it is removed there remains no obstacle to removal and replacing of the wire. Or, as shown in this case, this lower part may be in two sections, the bottommost section being only a plate, all above it being removable by simply unbolting. In such a case, the lift is very slight, a small fraction of an inch being enough, as it is only necessary to take the

weight and friction off of the section 39 to permit it to be withdrawn—yet there must be that much lift to release the block. The difficulty of stopping the powerful apparatus at 5 exactly the right point will be obvious. On the other hand, if it is not stopped in ample time, the bearings, supports, and other parts at the opposite end may be ripped to pieces. This frequently happens, with resulting very 10 heavy loss in repair costs and even greater loss through loss of time on the machine. In the present construction, the pivot connection completely eliminates this difficulty as it makes the roll practically "fool proof" as to 15 the operation of replacing or removing a wire.

It will be clear on reference to Fig. 1 that there are only three sets of bearings, altogether, and that all three sets are very easily and quickly accessible at any and all times. 20 In case of damage, with resulting need of repair or replacement, this is very important and results in a big saving in time in making the repairs as well as the saving of heavy loss in the operation and production of the machine 25 during the time it is idle for repairs. In the more recent constructions of the larger rolls, the lift at the free end is considerably more than above stated, as much as 4" in some, with proportionate multiplication 30 of dangers of damage at opposite end. The annular flanged plates at opposite ends of the shell, in addition to the functions given, perform the further function of dams to prevent the flow of water outwardly from the shell ends instead of through the perforated wall. As is well known, these shells rotate 35 at a high rate of speed so that water draining from the pulp through the shell to the interior of the shell does not get the chance to run out that it would with a stationary shell or one revolving at a low speed. The result is that water accumulates in the lower part of the shell faster than it can flow 40 through the perforations of that portion, and, therefore, unless prevented, runs out the ends and into the bearings or other working parts nearby with resulting damage. In the present construction, the annular plates at the 45 opposite ends act as dams to prevent this. They give a sufficient head to force the accumulating water to flow through the perforations, only, and, therefore, into the drip pans or other receptacles provided.

50 It is thought that the construction, operation, and use of the invention will be clear from the preceding detailed description, and it is to be understood that many changes may be made in the construction, arrangement, and disposition of the several parts of the invention within the scope of the appended claims, without in any degree departing from the field and intent of the invention, and it is meant to include all such within 55 this application, wherein the construction dis-

closed is merely illustrative of a single preferred form.

What I claim is:

1. A suction roll, a bearing housing therefor comprising sections, and pivotal connections between said sections whereby the suction roll in its bearing may be swung bodily in a vertical direction with its bearing without relative movement between said roll and bearing or said bearing and housing. 75

2. A suction roll comprising a perforated shell, a head at one end of said shell having an inwardly extending flange thereon defining an enlarged central opening in said head, a shoulder on the inner end of said flange 80 projecting into said opening, a second head secured to the opposite end of said shell and having a tubular journal thereon, a suction box in said shell, means projecting from said suction box into the journal of said second head to support one end of said suction box, the opposite end of said suction box having a socket therein, a journal in said socket projecting through the opening in said first head, a roller bearing mounted between the flange on said head and said journal and retained in place by the shoulder on said flange, a cover plate secured to said first head over said bearing and means for supporting the journals extending from said heads. 95

3. A supporting device for a suction roll having a perforated shell, comprising journals extending from opposite ends of said shell, a tubular housing encircling one of said journals, a bearing between said housing and journal, a supporting base beneath said housing, means for effecting a positive pivotal connection between said housing and said base, and a detachable support for the journal at the opposite end of said shell whereby this end of the shell may be moved vertically about the pivotal connection between said housing and base. 100

4. A device as in claim 3 wherein the pivotal connection between said base and housing comprises aligned lugs on said housing and base and a pintle pin extending through said lugs. 105

In testimony whereof I affix my signature.
